(57) **CLAIM**

The ornamental design for a body-fluid treatment module model kit, as shown and described.

DESCRIPTION

FIG. 1 is a front view of a body-fluid treatment module model kit of the present design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view.

This model kit is a learning kit for understanding the structure of a body-fluid treatment module.
